UNITED STATES PATENT OFFICE.

JOHN ASTROM, OF MILWAUKEE, WISCONSIN.

CONDENSING-APPARATUS PUMP.

No. 901,580.

Specification of Letters Patent.

Patented Oct. 20, 1908.

Application filed November 25, 1907. Serial No. 403,646.

To all whom it may concern:

Be it known that I, JOHN ASTROM, a citizen of the United States, and resident of Milwaukee, in the county of Milwaukee and 5 State of Wisconsin, have invented certain new and useful Improvements in Condensing-Apparatus Pumps; and I do hereby declare that the following is a full, clear, and exact description thereof.

10 My invention consists in what is herein-after particularly set forth with reference to the accompanying drawing and pointed out in the claims, its main object being to provide simple, economical and efficient 15 pumps for the separate removal of air and water from steam condensing chambers and to avoid commingling of said air and water in the pumps. However said pumps may be utilized for other purposes.

20 The drawing represents a sectional view of a condensing apparatus pump in accordance with my invention.

Referring by letter to the drawing, A indicates a water-chamber base portion of the 25 pump, and surmounting this pump-base is a condensing-chamber B and an overflow chamber C, valve-plates D, E, being interposed between said pump-base and the chambers.

30 The wall of the chamber B is provided with an inlet b for steam to be condensed, and the upper portion of said chamber is provided with an inlet c for injection-water, as well as an outlet d for accumulated air.

35 This upper portion of the chamber B is also provided with a pan bottom e having a vertical flange f around a central aperture of same, and suspended from the pan is a tray g approximately midway between said 40 pan and another pan h that is supported on lugs i in said chamber, the latter pan being provided with a vertical flange j around a central aperture therein.

The valve-plate D carries a series of valves 45 m that open from the chamber B into the pump-base A and close in the opposite direction, any suitable form of valve being employed. The valve-plate E carries a series of valves n similar to those aforesaid but 50 arranged to open from the pump-base into the chamber C and close in the opposite direction. The outlet of the chamber C is provided with an inwardly extending flange o whereby a cushion space is formed within 55 said chamber in the upper portion of same.

A cylinder F extends into the water-

chamber base A aforesaid through one end of same and an outer flange p of the cylinder is made fast to said base, the joint being water-tight. The inner end of the cylinder 60 is open, and its outer end is connected to a hollow head G, which head is provided with a partition q by which it is divided into compartments having valve-controlled openings by which communication is established between these compartments and said cylinder. The head-compartments are closed by covers r, s, and the valves t, u, controlling the communication between the cylinder F and said head are of any suitable construction. The 70 valve t opens into the cylinder and the valve u opens in the opposite direction. The upper end of the chamber B has pipe-connection H with the cylinder-head compartment containing the valve t, and the other cylinder-75 head compartment containing the valve u is provided with an outlet w.

In sliding fit with the cylinder F is a solid plunger I to which is attached a rod J that extends through a stuffing-box x and a gland y, the stuffing-box being in connection with an end of the water-chamber base A aforesaid. Reciprocatative motion is imparted to the rod and plunger by any suitable means.

Injection-water entering the chamber B, through the inlet c, falls in a sheet from the pan e to the tray g, thence to the pan h and finally into that portion of said chamber into which steam is admitted through the inlet b, 90 the result being a condensation of said steam, the water-of-condensation falling to the bottom of the aforesaid chamber.

When the plunger I is pushed into the cylinder F, the volume inside of the water-chamber pump-base A is correspondingly 95 enlarged and the valves m are unseated, whereby the water-of-condensation in the chamber B is drawn into said base, but the valves n remain seated. The reverse movement of the plunger proportionately decreases the volume inside the pump-base, and the pressure thus created causes the valves m to seat and the valves n to unseat, the water displaced by said plunger being admitted to 105 the overflow-chamber C from which it finally escapes through the outlet of same. When this last described movement of the plunger takes place, the space between the same and the head G is enlarged, the suction thus 110 created causing the valve t to unseat, whereby accumulated air from the chamber B is

drawn into the cylinder, the valve *u* remaining on seat. However when the first described movement of the plunger is repeated, the valve *t* seats and the valve *u* is unseated, 5 the air in the cylinder ahead of said plunger being forced into the outlet compartment of the head *G* to escape therefrom through the outlet *w* of same.

From the foregoing it will be understood 10 that the reciprocation of the plunger of the herein described pump will result in the removal of water and air separately from the condenser-chamber without commingling of 15 said air and water in the pump itself that is provided with separate inlets and outlets for the aforesaid air and water. This separate removal of air and water from the condensing-chamber results in an undisturbed desirable vacuum in said chamber, and said 20 pump is also capable of use for separating gaseous and liquid fluids accumulating in any receptacle to which it may be properly connected.

I claim:

25 1. A pump comprising a liquid fluid chamber having valve controlled inlet and an outlet, a cylinder having an open end in connection with the chamber and provided at its opposite end with a valve-controlled inlet and outlet head for gaseous fluid, and a 30 displacement plunger reciprocativ in said

chamber and cylinder but which separates the contents of same.

2. A pump comprising a liquid fluid chamber having valve-controlled inlet and 35 outlet, a cylinder having an open end in connection with the chamber and provided at its opposite end with a hollow head divided into valve-controlled inlet and outlet gaseous fluid compartments, and a displacement 40 plunger reciprocativ in the said chamber and cylinder but which separates the contents of same.

3. A pump comprising a liquid fluid chamber having a valve-controlled inlet and 45 outlet, an overflow chamber surrounding the outlet of the one aforesaid, a cylinder having an open end in connection with the first chamber and provided at its opposite end with a valve-controlled inlet and outlet head 50 for gaseous fluid, and a displacement plunger reciprocativ in said liquid fluid chamber and cylinder but which separates the contents of same.

In testimony that I claim the foregoing I 55 have hereunto set my hand at Milwaukee in the county of Milwaukee and State of Wisconsin in the presence of two witnesses.

JOHN ASTROM.
